AUTOMATIC CONTROL FOR WASHING MACHINES

Angus F. Hanney, Norwood, Ohio, assignor to
The American Laundry Machinery Company,
Cincinnati, Ohio, a corporation of Ohio

Application September 27, 1932, Serial No. 635,093

7 Claims. (Cl. 68—18)

This invention relates to automatic washing machines or any other machines where material is subjected to a series of different operations and it is desirable to automatically control the entire 5 cycle of operations. The invention has particular application to automatic washing machines or the like where a batch of material to be washed is treated for a given length of time during which it is subjected to the action of water and various 10 materials, which may be generally characterized as detergent materials, such as soap, soda, bleach, sour, and bluing, it being necessary during the cycle of operations to first admit to and then withdraw from the container, in their proper 15 order, the water and these various detergent materials, the goods being subjected to the action of the various materials, or mixtures thereof, for differing periods of time.

The invention has for its object to generally 20 improve such mechanism, and particularly to provide a mechanism which is of relatively simple form and for the most part of mechanical nature, and which can be readily adapted for the control of any type of washing machine, including 25 washing machines already in use.

A further object of the invention is to provide 30 automatic control mechanism of the jacquard type, in which all control operations may be effected by a master device which is of very simple 35 form and can be readily replaced by other devices so as to vary the formula or cycle of operations, making it possible for the laundryman to secure or carry on hand master control devices which will subject his laundry work to any desired 40 number, arrangement and sequence of operations.

A further object of the invention is to provide 45 automatic control mechanism of the character described in which the master device is a simple plate provided with perforations arranged in order along rows, enabling the master device to be progressively moved through the mechanism to bring said perforations in turn to an operating zone where they cooperate with other parts of the mechanism for the control of various mechanisms or devices and secure the desired order and timing of the various operations.

A further object of the invention is to generally 50 improve the various control mechanisms, and more particularly to provide improved means for automatically determining the level of liquid in the container and its temperature, as well as to 55 terminate the entire cycle of operations and at all necessary times to advise the operator when

performance of any duty by him is necessary or desirable.

Further objects of the invention are in part 5 obvious and in part will appear more in detail hereinafter.

In the drawings, which represent one suitable embodiment of the invention, Fig. 1 is an end elevation of the washing machine as a whole, with the automatic control mechanism attached to the near end thereof; Fig. 2 is a side elevation of a 10 portion of the automatic control mechanism, showing it on a larger scale, detached from the washing machine, and in normal position with all parts at rest ready to begin a cycle of operations; Fig. 3 is a plan view, corresponding to Fig. 2; 15 Fig. 4 is a longitudinal sectional elevation on approximately the line 4—4, Fig. 3, showing the parts in position with the master control sheet elevated; Fig. 5 is a similar view, showing the master control device depressed and the operating bar advanced; Fig. 6 is a detail longitudinal 20 sectional view on approximately the line 6—6, Fig. 3, showing the mechanism for returning the carriage to initial position, and with the carriage in such position; Fig. 7 is a similar view, showing the operation of said mechanism, with the carriage advanced and ready to be returned; Fig. 8 is a detail sectional elevation, illustrating the 25 thermostatic mechanism for controlling the water temperature; and Fig. 9 is a detail elevation, partly in section, showing the water level control mechanism.

While the invention may be employed for use 30 in any type of machine which performs a sequence of operations with various materials upon 35 the work, for convenience it has been illustrated without any intention of limitation to an automatic washing machine. As will appear more in detail hereinafter, the washing machine is of ordinary type involving a tub in which rotates a 40 drum containing the work, the control mechanism being arranged to control the driving of said tub, the supply to and withdrawal from the tub of the water and the various detergent liquid materials, such as soap, soda, bleach, sour, and 45 bluing, the supply of heating steam; to control the level of liquid and its temperature at various stages of the operation; and finally, to actuate a suitable alarm or indicator for advising the operator of any duty he may be required to perform. To accomplish all of these results I make 50 them all subject to or sensitive to a single master control device, which may be of any suitable form so long as it is of simple construction, is adapted to properly cooperate with other parts of the 55

mechanism, and is capable of quick and convenient replacement, such as for the purpose of changing the formula. In the form which I have elected to illustrate for the purposes of this application, the master control device is a piece of sheet material which may be made of any substance strong enough for the purpose but which preferably is a relatively thin strong metal sheet of generally rectangular form and provided with 10 rows of perforations, one row for controlling each of the several operations or results to be performed or produced. The metal sheet is progressively moved through the machine in a direction parallel with the length of the rows of perforations, 15 with a slow motion, either continuous or intermittent, and intermittently, at regular intervals,—for example, every fifteen seconds or every minute,—is moved transversely to its plane, such motion being utilized to render effective or 20 effective each one of the chains of operating mechanism to a device to be controlled, such as a valve, a release trip, a semaphore or the like, according to whether there is a hole or a blank 25 space in the master device at that portion of said device which is effective at the particular time. In other words, assuming the entire cycle of operations to require thirty minutes and that the master device is advanced every fifteen seconds, there will be one hundred twenty operations of 30 said master device, and at each such operation the device is capable of rendering all of the chains of operating mechanism effective, but is actually effective upon only those chains of operating mechanism where the master device is provided 35 with a perforation, blank portions of the master device being ineffective to produce operations of said chains of mechanisms. Therefore, for convenience and to the end of orderly discussion, and because the controlling effect upon all of the several chains of mechanism is the same, I will first 40 describe the master device and its mode of operation, following with detailed descriptions of the several chains of controlling mechanism, as may be necessary.

Only brief reference to the washing machine is 45 necessary. It comprises the usual outer casing or tub 1 mounted on a suitable frame and containing within it a rotatable drum 2 actuated through suitable gearing by any driver, such as the electric motor 3, the circuit to which may be of any suitable form capable of control for starting by a manually operated switch 4 and of control for stopping by a switch 5 operated automatically, as will appear.

Hot water is supplied to said machine by way of 50 a pipe 6 provided with a controlling valve having a stem 7, and cold water by way of a pipe 8 having a controlling valve, the stem of which is indicated at 9, the two pipes 6, 8 delivering to a pipe 10 which discharges into the tub 1. Cold water is also supplied by way of a pipe 11 and valve 12 and pipe 12a for actuating a siphon or injector.

Steam for heating the contents of the tub, as 55 well as for other purposes, is supplied by way of a pipe 13, flowing through a valve 14 to a pipe 15 discharging into the tub 1 and other valves shown in dotted lines in Fig. 2, one communicating with a pipe 16 for actuating the drain valve and the other with a pipe 17 for actuating an injector.

The two injectors referred to are utilized for 60 forcibly delivering into the tub detergent materials placed in the bowls 18, 19, the first of which is used for soap, soda and bleach and the second of which is used for sour and bluing, which

are kept separate to avoid chemical action between them, as will be readily understood. The two bowls are placed at different levels, as shown in Fig. 1 so that the operator has full and complete access to the top of each bowl and when filling one will not allow any of the liquid to drip into the other with harmful results.

20 represents one of a series of semaphores, which are alike as to construction and operation, so that description of one will suffice for all, each 10 semaphore, when moved to indicating position, advising the operator that some duty is necessary by him, as well as the nature of the duty. Rise of one semaphore, for example, will advise the operator that he should supply, for example, three 15 quarts of soap to bowl 18, while another semaphore may indicate the necessity of supplying three quarts of bluing to bowl 19. Each semaphore may cooperate with a suitable audible alarm, such as an electric bell actuated by a switch 20 21 which in turn is operated by the corresponding semaphore, as will appear.

The formula control mechanism, including the perforated plate master control device before referred to, and its operating mechanism, may 25 be driven in any suitable manner. In the arrangement shown the master plate is supported in a horizontal plane upon a carriage which is traversed back and forth along a rising and falling cradle and the motion of these parts is produced by a single continuously rotating shaft. Said shaft, marked 22 in Fig. 1, extends crosswise of the frame 23 of the control mechanism, being mounted in suitable bearings therein and being provided at one end with a gear 24 (Fig. 35 1) driven by speed reducing gearing shown in dotted lines, from an electric motor 25, whose circuit is also subject to the automatic and manually operated control switches 5, 4. Motor 25 is preferably a constant speed motor and the 40 gearing connecting it to shaft 22 is so proportioned as to rotate said shaft at definite speed, say one complete rotation every fifteen seconds or every minute in accordance with the number of operations of the master plate which are desired during the complete cycle of operations.

The master plate, indicated at 26, is provided with rows of perforations 27, one row for each of the various operations to be performed or results to be produced, as indicated by the legends in Fig. 3. Said plate has a snug fit in a seat for it in a carriage 28, which is a mere rectangular frame provided with a groove or recess to support the edges of the plate 26 so that both its upper and lower surfaces are exposed. Suitable means may be provided for insuring insertion of the master plate into its seat in only one position, such as one or more openings 29 distributed at irregular intervals along its edges and adapted to receive small dowel pins 30 on the carriage. The several perforations, according to their order and arrangement on the plate, produce the automatic control action, and the blank surface of the plate may bear legends opposite the corresponding rows of perforations and indicating their duty, as well as any other information desirable to or necessary for the laundryman or machine operator.

Carriage 28 slides back and forth on suitable ways on a cradle marked generally 31, which 70 is also of rectangular form but is provided at its opposite sides with posts 32 mounted to slide vertically in ways 33 on the main frame, so that the cradle has nothing but up and down motion. Said cradle is actuated from the shaft 22 which,

midway between the sides of the machine, is provided with a crank arm 34 having a roller 35 cooperating with a foot 36 on one arm of a lever 37 pivoted at 38 on a cross bar and having an elongated slot to receive a cross rod 39 connecting the two posts 32. The other end of the lever 37 may be provided with a counterweight 40. Shaft 22 rotates in the clockwise direction, Fig. 4, making one complete revolution at each 10 interval, say one every minute. Normally the cradle and carriage are in their lowermost position indicated in Fig. 5, since the counterweight 40 counterbalances only a portion of the weight of the cradle and carriage simply to reduce the 15 duty of the shaft 22. Therefore, every time the arm 34 comes around, its roller engages the foot 36 and swings lever 37 from the position shown in Fig. 5 to that in Fig. 4, holding the parts in the upper position while the roller is travelling 20 over the curved portion 41 of the foot 36, and when the roller finally leaves the lever the cradle and carriage return by gravity to the position shown in Fig. 5 but with negligible shock due to the substantial balancing effect of weight 40.

25 Each up and down motion of the cradle and its parts is accompanied by advancing motion of the carriage along the cradle, the amount of each advance motion being equal to the distance between successive perforations 27 along the several rows thereof. In other words, it is the increments of advance of the carriage that determine the spacing of the perforations in the master plate. Step by step advance of the carriage along the cradle is accomplished by pawl and 30 ratchet mechanism as follows:—

The cradle is provided with a transversely extending rock shaft 42, journaled in its sides, said rock shaft at each side of the cradle carrying an arm 43 to which is loosely pivoted at 45 a pawl 44 capable of adjustment by a screw 46 to set the operating end of the pawl with reference to the ratchet to be operated. Rock shaft 42 at one side of the machine carries an arm 47, the free end of which projects beyond the end 40 of a pawl 48 loosely pivoted at 49 on a portion of the stationary frame and normally resting by gravity against a stop so that it lies in the position shown in Fig. 2. Each time the cradle is raised arm 47 lifts the pawl 48, which drops down 50 behind it and forms a stop to engage the arm 47 when the cradle returns, so as to move the shaft 42 clockwise in Fig. 5 until arm 47 passes the pawl 48, when the shaft 42 and its attached parts are returned by gravity or by the 55 force of a spring or springs to their initial position, shown in Fig. 5, with the arm 43 resting upon a stop pin 50.

The aforesaid rocking motion of shaft 42 causes the pawls 44 to engage in the teeth of 60 ratchets 51, one extending lengthwise along each side portion of the frame of the carriage 28, and to advance said carriage a distance a little greater than the distance between the teeth of ratchet 51. Any excess is taken up when the parts 65 return toward initial position by the effect of a weight 52, Fig. 7, connected to the carriage by a cable 53 passing over a pulley 54 and tending to return the carriage to its original position shown in Fig. 4. A pawl 55 limits return 70 operation so that the carriage is accurately advanced one tooth at each operation, and said pawl is operated to permit full return of the carriage at the conclusion of the cycles of operations in a manner now to be described.

75 Referring to Figs. 6 and 7, 56 indicates a

weighted lever pivoted at 57 and normally tending to turn counterclockwise. It is pivoted on a bar 58 longitudinally slidable on the cradle and urged toward the left by a tension spring 59. The other end of said bar lies adjacent a pin 60 5 on a crank or lever 61, said pin also extending under the long arm of the pawl 55. Crank or lever 61 is mounted to turn in the frame 31 with sufficient friction in its bearings or with relation to said frame so that it will remain in any position to which it is forcibly moved against said friction. The upper end of lever 56 is provided with a hooked end 62 which normally lies beneath and travels along a blank portion of the master control plate 26, but said control plate 15 at a point near that end corresponding to the end of the cycle of machine operations is provided with a slot 63, into which the hooked end 62 of the lever 56 rises, as shown in Fig. 7, just before the end of the cycle of operations. Further advance movement of the carriage to the right in Fig. 7 causes the carriage to carry with it the lever 56 and bar 58, moving them to the right and turning the crank or lever 61 clockwise 20 so that it disengages the hold back pawl 55 from 25 the ratchet 51, permitting the carriage 28 to be completely returned from right to left to its original position, shown in Fig. 6. On its return to such position the carriage engages and opens the automatic switch 5, breaking the circuits to 30 the motors 3, 25, and terminating or stopping all operations. Furthermore, return of the carriage to its original position causes a lug 28a, depending from the right hand end of the carriage 35 35 in Figs. 6 and 7 to engage the pin 60, as shown in Fig. 6, and turn it from the position shown in Fig. 7 to that in Fig. 6, enabling the pawl 55 to re-engage with the ratchet 51. The operator now removes the washed goods from the drum 2 and inserts a new load, thereupon actuating the 40 hand switch 4 and starting another cycle of operations which continues until completed in the manner described.

To prevent interference with the cycle of operations by the operator, means is provided for 45 preventing the operator from manually advancing the carriage 28, such means comprising a pawl 64 pivoted on the cradle, Fig. 5, normally held by gravity in locking engagement with a ratchet 65 on the upper face of the carriage 28, 50 said pawl having a pin 66 lying in a slot 67 of an arm 68 pivoted at 69 to one of the levers 43. When shaft 42 is rocked clockwise in the manner before described, arm 68 moves upwardly, the lost motion in the slot 67 is taken up and pawl 55 64 is disengaged from its ratchet, all previous to engagement of pawl 44 with its ratchet, and the carriage 28 is moved to the right before pawl 64 is again engaged with its ratchet.

Shaft 22, in addition to the arm 34, carries 60 two arms 70, one on each side of the machine, each arm being equipped with a roller 71 and adapted to actuate one arm 72 of a lever 73 pivoted at 74 in the machine frame, the two levers 73 being connected by links 75 to blocks 65 76 which are reciprocated on guide rods 77, the two blocks being connected by an operating bar 78 extending crosswise of the machine and adapted to engage with the hooked ends 79 of a series 70 of pull rods 80, one of which is operated for the production of each operation or result desired. The series of pull rods 80 lie in parallel relation, as shown in Fig. 3, each extending through a closed eye 81 on a vertically extending pin 82, the 75 several pins 82 being slidable vertically in open-

ings in upper and lower stationary guide bars 83, and their lower ends lying adjacent to and just above the master plate 26. The several pull rods 80, at their right hand ends, Figs. 1, 2 and 3, are pivotally connected to various levers for producing the controlling effects, and they can swing to a limited extent in a vertical plane about their pivotal connections to said levers, as an axis. The parts are so timed that at each revolution of shaft 22, not only is the carriage 28 advanced one step, but also the operating rod 78 is moved to the left from the position shown in Fig. 4 to that shown in Fig. 5 and is then returned by the effect of the counterweight 84 on lever 73. During its motion it advances with it, to the left in Fig. 4, all those pull rods whose hooked ends 79 have not been elevated by upward motion of the master plate 26. In other words, assuming the master plate to be in any given position during its series of positions through the cycle of operations, in each of the rows of holes corresponding to all of the operations to be produced there will be a hole in the plate 26 when any particular operation is to be produced or a blank area when no operation is to be produced, so that when the plate 26 is elevated, as described, the pins 82 corresponding to the operations that are to be produced are not elevated because said pins are opposite holes 27 and are not elevated by the plate, but all remaining pins are elevated by the blank areas of the plate and the corresponding rods 80 are also elevated, so that when the operating bar 78 advances to the left in Figs. 4 and 5 it moves only selected ones of the rods 80, as shown in Fig. 5. The master plate therefore, by its arrangement of perforations, becomes the selector and key to the number, arrangement and sequence of various operations. On its return to initial position, by motion to the right in Fig. 5, the operating bar 78, because of the inclination of its upper face, idly lifts the hook ends 79 of those pull rods which it has not advanced, so as to pass beyond the same ready for their operation the next time, if required.

The several rods 80, when operated, are all operated in the same manner and with the same amount of motion, and their advance motion is transferred by levers, links or other mechanism to the parts to be controlled, which will now be referred to in detail.

Referring first to the hot water supply, one of the rods 80 is connected to one arm of a bell crank lever 85, Fig. 2, the other arm of which is connected by a link 86 to arm 87 on the stem of the hot water supply valve. Moving with said arm 87 is a toothed segment 88, which cooperates with a gravity pawl 89 connected by link 90 to a bar 91 attached to a rod 92. Similar mechanism is provided for operating and controlling the cold water valve, with the exception that the same bar 91 releases the pawls of both the hot water and cold water supply valves. When a supply of hot or cold water or both is required, one or the other or both of the proper pull rods are actuated to open the necessary water valves. The valves are held open, even after return of the operating bar 78 by the pawls 89, until said pawls are released by upward movement of rod 92, whereupon the valves close. Rod 92 is actuated to control the level of liquid supplied to the washing machine tub, for which purpose it is connected at its lower end (Figs. 1 and 9) to one arm 93 of a lever pivoted at 94, said arm having a counterweight 95, and the other arm 96 of the

lever carrying an open top bucket 97 having a small vent port 98 in its bottom and lying beneath the discharge opening 99 in a reservoir 100 in which are located two over-flow pipes communicating at 101 with the tub 1. These two over-flow pipes are respectively a low level pipe 102 and a high level pipe 103. The upper end of each of said pipes is closed by a normally closed pivoted valve 104, each valve being connected by a link 105 to an arm 106 connected by a link 107 to a lever 108 actuated by a lever 109 connected to one of the pull rods 80 (see Figs. 1 and 9). The levers 106 serve as latch levers, for which purpose they are provided with pins adapted for cooperation with latch levers 110 connected by links 111 to a rod 112 connected to the arm 96.

If at any particular time when water or other liquid is to be delivered to the tub, it is desired to produce and maintain a low level of liquid, say four inches in depth, the proper pull rod 80 is actuated to lift valve 104 on the low level pipe 102, and said valve is latched in its open position by its latching parts 110, 106. The water valve or valves are now opened and water flows into the tub, rising from the bottom of the same until finally water flows out through the top of the over-flow pipe 102, into the reservoir 100, from which it is delivered to the bucket 97. The vent hole in said bucket is restricted so that while said bucket will ultimately drain completely, its drainage is slow and practically immediately the first overflow fills the bucket and causes it to move down, raising the arm 93 and by means of link 92 releasing the water supply valve for self-closing operation. The same motion pulls down the link 112 and releases the latch so that valve 104 closes. If a high level of liquid is to be produced and maintained, say twelve inches, the proper pull rod 80 actuates the valve 104 at the top of the high level pipe 103 and water is delivered to the tub until such level is reached, whereupon the high level valve 104 is closed and the water valves close, in the same manner before described. During the succeeding interval the bucket 97 drains and returns to its initial position shown in Fig. 9, ready for another operation.

In connection with the water supply, means is also provided for producing and maintaining a desired temperature of the liquid and vapors within the tub. Of course, some regulation of temperature may be secured by properly proportioning the amounts of hot and cold water, but chiefly when a temperature higher than that of the hot water is desired, the temperature is raised by the supply of heating steam to the tub and the supply of such steam is thermostatically controlled so as to produce and maintain any desired temperature. The thermostatic control mechanism is housed in a casing 113 mounted at the top of the mechanism, as shown in Figs. 1 and 8. Within this casing is located an expandible and contractible heat responsive element 114 sensitive to the temperature within the tub and which, for example, may be a Bourdon tube communicating by a small conduit 115 with a bulb 65 not shown but located within the tub and containing expandible liquid or gas, as is well known. Movement of the Bourdon tube actuates a lever 116, the lower arm of which carries a contact 117 cooperating with a contact 118 on an arm 119 pivoted at 120. The two contacts 117, 118, are connected in a circuit 121 through a suitable source of current 122, said circuit also including an electromagnet 123, and a tilting mercury switch 124 of well known form. One of the rods 75

80 is connected to a lever 125 carrying the tilting mercury switch, which lever in turn is connected by a link 126 to a lever 127 for actuating the steam supply valve 14 before referred to. The 5 upper end of lever 125 cooperates with a notch in a latch lever 128 pivoted at 129 and connected by a link to the movable core 130 of electromagnet 123.

When it is desired to produce and maintain a 10 relatively high temperature within the tub, say 180° F., the proper pull rod 80 is actuated, swinging lever 125 to the dotted line position, Fig. 8, and closing the circuit 121 at the mercury switch 124. This circuit is not completely closed, however, because it is still open at contacts 117, 118. The link 126 and lever 127, however, open the 15 steam valve and steam flows into the tub until the rise in temperature affects the thermostatically responsive bulb referred to, expands Bourdon tube 114, and turns lever 116 in the clockwise direction, Fig. 8, to close the circuit 117, 118. Contact 118 is a screw which may be adjusted to set the device at a desired temperature, say 180°. When this temperature is reached the 20 circuit is closed, as described, electromagnet 123 is energized, its core rises and the latch 128 releases lever 125 so that the steam valve returns to its closed position by its own spring or the like.

Means is also provided for producing and maintaining a lower temperature, say 140° F., which 30 includes means for adjusting the lever 119 and the contact 118 carried thereby. This means is also shown in Fig. 8. The proper pull rod, corresponding to 140° F., actuates a lever 131 normally 35 held against a stop 132 by a spring 133, the other arm of said lever being connected by an adjustable link 134 to lever 119. Lever 131, when turned clockwise in Fig. 8, moves the contact 118 closer to contact 117 and reduces the amount of expansion of the Bourdon tube necessary to close the 40 circuit. Lever 131 is held in its new position by the spring latch 135, connected by link 136 to a lever 137 which in turn is connected by a link 138 to one arm of the lever 128. As a result, when 45 it is desired to produce and maintain the lower temperature, both of the levers 125, 131 are moved by their pull rods 80 to the latch position and both are unlatched simultaneously by energization of the magnet 123, which occurs when the circuit 121 is closed by the effect of the Bourdon tube.

Means is also provided for forcibly supplying 50 various detergent liquids from the bowls 18, 19 to the washing machine tub. Liquid poured into the bowl 19 is delivered from the bowl 19 into the washing machine by an injector 139, Fig. 1, which has a suction pipe 140 extending nearly to the bottom of the bowl 19 and a discharge pipe 141 leading into the pipe 10 which delivers water to the machine tub. The injector 139 is operated 55 by water delivered to it by way of pipe 12a from the valve 12, and valve 12 is actuated by a lever 142 actuated by one of the pull rods 80. A similar injector, but in this case actuated by steam supply and not by water, is provided for delivering 60 to the tub liquids deposited in the bowl 18. Accordingly, assuming that the operator has poured the requisite quantity of the liquid into the proper bowl, when the times comes to deliver it 65 into the washing machine, one of the pull rods 80 opens the steam or water supply valve to the proper injector and the detergent material is sucked out of its bowl and discharged into the washing machine tub.

70 Means is also provided for advising the operator

when to insert detergent liquids in the bowls 18, 19, such as the several semaphores 20 before referred to. These semaphores are usually made of sheet metal or the like, and are pivoted at 143 at the front edge of the casing 113, each semaphore 5 being provided with an arm 144 connected by a link 145 to a lever 146 actuated by one of the pull rods. The arms 144 are arranged each to cooperate with a switch 21, so that when a semaphore is moved up to indicating position, its arm 10 144 closes its switch 21 and energizes a very simple bell circuit to a source of current, causing an audible alarm and instructing the attendant to inspect the machine and supply the required detergent to its bowl. When that has been 15 accomplished the operator can manually move the semaphore to its down or non-indicating position, which permits the switch 21 to open and restores the parts to their initial position ready for another operation.

Means is also provided for automatically controlling the drain valve for the tub 1, which valve is conventionally shown at 147, its locking stem being provided with a bell crank lever 148, one arm of which is connected by a rod 149 to a movable piston within a fluid pressure cylinder 150, operating pressure for which comes by way of steam pipe 16. In said pipe is a valve (not shown) actuated by a lever connected to one of the pull rods 80. When said valve is opened, in 30 the manner before described, steam flows through the pipe 16 to the cylinder 150 and moves over its piston, thereby opening the drain valve. The second arm 151 of the lever 148 moves down to latching position where it is latched by a pivoted 35 latch 152 actuated by a link 153 connected at its upper end to one arm of the lever 37. Said lever is oscillated once for every revolution of shaft 22, so that whenever the drain valve is opened it is almost immediately closed, or in any event, is closed before the rotation of shaft 22 is completed, but the drain valve is of very large area or size, so large, in fact, that it dumps the entire liquid contents of the washer in a matter of just a few seconds, as will be readily understood.

With the mechanism described, it is possible to produce any desired washing formula. By properly punching openings in the master control plate 26 and inserting said plate into the machine, a complete cycle of operations is produced by operating the manual switch 4, which starts both electric motors by closing the operating circuit in the usual manner, and causes said motors to run until the cycle is completed and the automatic switch 5 is opened. During such 50 cycle of operations the cradle is periodically elevated and each time it moves up the carriage 28 is in a new position. At each operation of the cradle and carriage, all rods 80 are elevated except those which it is desired to operate, and the advance motion of bar 78 pulls the selected rod or rods forward and produces actuation of the proper valve, lever, latch or other part in the manner before described. Ultimately the carriage 28 is released and returns to its initial position and the cycle may be resumed when the washer drum is unloaded and reloaded. A complete new formula may be installed and put into operation in a machine by a simple change of the master plate 26.

75 A complete cycle of operations accompanying one full rotation of shaft 22, briefly described, is as follows:—

Assuming the parts in the position shown in Fig. 1, with the cradle down, the first effect is to 75

raise the cradle, the carriage and master plate moving up with it to the position shown in Fig. 4, where certain of the pins 82 have been raised to make the operating bar 78 ineffective upon their pull rods, others of the rods 80, where there are holes in the master plate, remaining elevated ready for actuation by bar 78. Next, the bar 78 travels to the left to the position shown in Fig. 5, actuating the selected pull rods 80, said bar 78 then returning to its initial position. During its operation the cradle has been held elevated by engagement of the roller 35 with the curved portion 41 of arm 36. When bar 78 has been moved from its initial position, the cradle begins to move downward, and when the master plate has moved down so that all pins 82 are out of the holes in the plate, the lever 47 engages pawl 48, rocks shaft 42 and advances the carriage one step on the cradle to a new position where it is held by pawl 55. All parts are now ready for another operation.

Similar operations occur successively in order until the full formula has been completed, whereupon the carriage 28 is released and returns to initial position and actuates the automatic switch 5 to open the motor circuit and terminate all operations. The washer is thereupon unloaded and reloaded and a new series of operations started by closing the manual switch 4.

As stated before, switches 4 and 5 are in the same controlling circuit for the motors, a circuit which, for example, may be the same type of three-wire circuit used in house illumination where a given lamp must be subject to control from two points, say upstairs and downstairs. Both switches must therefore be closed to complete the motor circuit. Switch 4 is moved manually in succession to its two closed positions and switch 5 is moved automatically in succession to its two closed positions. Switch 5 may be of any suitable form, but is shown as embodying a rotatable member turned 90° at each operation. The rotatable part carries four spring arms 5a, 5b, etc. It is mounted on a part of the cradle 31, as shown in Fig. 5, with the arm 5a projecting up into the path of movement of the carriage 28. Referring to Fig. 5, when the carriage 28 is released it moves to the left and engages arm 5a and rotates the switch part to the position shown in Fig. 4, and the following arm 5b yields and assumes the position shown in full lines, Fig. 4. The motor circuit is now open and a new formula or series of operations is started by turning the manual switch 4 to the dotted line position, Fig. 4, which again closes the motor circuit. The carriage begins to advance to the right in Fig. 4 and when it finally passes away from switch 5 the arm 5b yieldingly springs up to the dotted line position in that view, ready to be engaged by the carriage when the formula is completed and the carriage returns. The third formula is then started by turning the switch 4 to its next closed position, and so on.

65 What I claim is:

1. In an automatic machine of the class described, jacquard apparatus arranged to control the operations of said machine, comprising a jacquard plate having a drive providing for its forward step by step movement from an initial position to another position, a plurality of rods, actuating means for said rods, and for each rod, means for controlling the effectiveness of said actuating means upon said rod responsive to the position of said plate, and means operatively as-

sociating said rod with a part of said machine to be controlled in timed relation with other parts of the machine, and means controlled by said plate and providing for its return by reverse movement to said initial position. 5

2. In an automatic machine of the class described, jacquard apparatus arranged to control the operations of said machine, comprising a jacquard plate having a drive providing for its forward step by step movement from an initial position to another position, a plurality of rods, actuating means for said rods, and for each rod, means for controlling the effectiveness of said actuating means upon said rod responsive to the position of said plate, and means operatively associating said rod with a part of said machine to be controlled in timed relation with other parts of the machine, means associated with said plate to prevent its advancement by the operator ahead of said cyclic advance. 10 15 20

3. In an automatic machine of the class described, jacquard apparatus arranged to control the operations of said machine, comprising a jacquard plate having a drive providing for its forward step by step movement from an initial position to another position, a plurality of rods, actuating means for said rods, and for each rod, means for controlling the effectiveness of said actuating means upon said rod responsive to the position of said plate, and means operatively associating said rod with a part of said machine to be controlled in timed relation with other parts of the machine, means to return said plate to its initial position, and means operated by said plate for stopping said machine upon said return of said 30 35 plate. 25

4. In an automatic machine of the class described, jacquard apparatus arranged to control the operations of said machine, comprising a reciprocable cradle, a carriage slidably thereon, and a rectangular jacquard plate mounted on said carriage, said plate and carriage having means cooperative to prevent mounting of the plate on the carriage in any but one plate position, a drive for said carriage, providing for its said step by step movement from an initial position to another position, a plurality of rods, actuating means for said rods, and for each rod, means for controlling the effectiveness of said actuating means upon said rod responsive to the position of said plate, 40 45 50 and means operatively associating said rod with a part of said machine to be controlled in timed relation with other parts of the machine. 55

5. In an automatic machine of the class described, jacquard apparatus arranged to control the operations of said machine, comprising a jacquard plate having a drive providing for its forward step by step advance movement from an initial position to a final position, means to retain the plate in intermediate positions to which it 60 has been advanced by said drive, means to release said plate from said drive after attainment of said final plate position, means for automatically returning the plate to its initial position after its said release, a plurality of rods, actuating means 65 for said rods, and for each rod, means for controlling the effectiveness of said actuating means upon said rod responsive to the position of said plate, and means operatively associating said rod with a part of said machine to be controlled in 70 timed relation with other parts of the machine. 75

6. In an automatic machine of the class described, jacquard apparatus comprising a vertically reciprocating cradle, a carriage slidably horizontally thereon, a master plate supported on 75

said carriage and provided with perforations in rows extending in the direction of travel of said carriage, ratchet mechanism for advancing said carriage step by step, a series of pins, one for each 5 row of perforations, each pin being mounted for actuation by said plate upon vertical movement of said cradle, dependent upon whether or not said plate in its instant advanced position is perforated at said pin location, a rod slidably supporting each pin, a reciprocating operating bar, each rod being arranged to be adjusted by its pin 10 between an idle position clearing said bar and an operating position wherein it is engaged and moved by said bar, means operatively connecting 15 each rod with a part of said machine for controlling an operation thereof in timed relation with other operations of the machine, means tending to return said carriage and plate to initial position, a hold-back device normally restraining such 20 carriage return movement, and means controlled by said plate for actuating said hold-back device for permitting the carriage to return to initial position following predetermined advancement therefrom.

7. In an automatic machine of the class described, jacquard apparatus comprising a vertically reciprocating cradle, a carriage slidable horizontally thereon, a master plate supported on said carriage and provided with perforations in 5 rows extending in the direction of travel of said carriage, ratchet mechanism for advancing said carriage step by step, a series of pins, one for each row of perforations, each pin being mounted for actuation by said plate upon vertical movement 10 of said cradle, dependent upon whether or not said plate in its instant advanced position is perforated at said pin location, a rod slidably supporting each pin, a reciprocating operating bar, each rod being arranged to be adjusted by its pin 15 between an idle position clearing said bar and an operating position wherein it is engaged and moved by said bar, means operatively connecting each rod with a part of said machine for controlling an operation thereof in timed relation with other operations of the machine. 20

ANGUS F. HANNEY.
